UNITED STATES PATENT OFFICE.

JAMES B. KIRBY, OF CLEVELAND, OHIO.

WASHING MACHINE.

1,407,201.

Specification of Letters Patent. Patented Feb. 21, 1922.

Application filed April 11, 1921. Serial No. 460,451.

To all whom it may concern:

Be it known that I, JAMES B. KIRBY, a citizen of the United States, residing at Cleveland, in the county of Cuyahoga and State of Ohio, have invented a certain new and useful Improvement in Washing Machines, of which the following is a full, clear, and exact description, reference being had to the accompanying drawings.

10 This invention relates to clothes washing machines and has for its special object the provision of a small, light, and portable, power-operated mechanism, which can be applied to and used in connection with set 15 wash-tubs, portable wash-tubs, and the like, and easily stored away after the washing is done. Other objects of the invention are the provision of mechanism of this character which will wash the clothing very 20 thoroughly and quickly and with a minimum of wear; the provision of mechanism which will stir and rearrange the clothing very completely during the washing operation, but without entangling the articles 25 either with each other or with the mechanism; the provision of improved and simplified clothes-washing mechanism of the pounder type possessing both a vertical motion and a rotating motion; the provision 30 of mechanical means of a peculiarly simple type for the operation of a pounder type washing apparatus; the provision of a new and improved mechanical movement for devices of this character; the provision of new 35 and improved expedients for preventing overloading of a machine of this nature; the provision of new and improved splashing preventing means; while further objects and advantages of the invention will become 40 apparent as the description proceeds.

In the drawings accompanying and forming a part of this application I have shown one operative mechanism in which my inventive idea can be embodied, together with the mode of application of the same to a rectangular casing such as a domestic set tub, but it will be understood that these drawings are intended only to illustrate the principles of my invention and not to limit me either to this special mechanism or to this kind of a receptacle. In these drawings Fig. 1 represents a side elevation of my complete washing machine as applied to a wash tub, the latter being shown in sec-

tion and the cover being shown in place. 55 Fig. 2 is a top plan view of the parts shown in Fig. 1, the cover being omitted and a part of the gear box being shown in section; Fig. 3 is a vertical sectional view corresponding to the broken line 3—3 of Fig. 2 and drawn 60 to enlarged scale; Fig. 4 is a vertical sectional view corresponding to the line 4—4 of Fig. 3 and looking in the direction of the arrows; and Fig. 5 is a detail view showing the free end of the pounder arm and 65 associated parts.

Describing by reference characters the parts shown in these drawings, 1 represents a gear casing supported with its plane approximately horizontal, having projecting laterally from one side an electric-motor casing 2 and having projecting from its bottom the bracket 3 provided with the horizontal pivot bearing 4, said bracket also serving as one side of a clamping member whereby 70 the device is attached to the wall 5 of a tub or like receptacle, the other clamping member comprising a screw 6 carried by a lug 7 formed on the motor casing. Journaled in the gear box is a vertical shaft 10 having 75 secured to its upper end the crank 11 whose free end is formed with the hemispherical, socket 12 receiving the ball 13 which is carried by one branch 14 of the arm 15; the other branch 16 of said arm has at its end 80 the offset longitudinally-bored, portion 17. Slidably and rotatably mounted in this bore is the shank 18 of a T bolt whose arms 19—19 are journaled in the bearings 4—4; the end of the shank 18 projects for a distance beyond the bore and is provided with 85 the removable collar 20 beneath which is interposed the compression spring 21.

Inside the gear-box 1 the shaft 10 is provided with a spur-gear 24 rigidly keyed there- 95 to and the motor-shaft 25 is provided with a worm 26 located beneath this gear and meshing with the worm-wheel 27 loosely sleeved on the vertical gudgeon 28. I have shown this gudgeon as removably secured in place 100 by the set screw 29 whose head is concealed by the plate 30 which covers the main portion of the gear box 1; and loosely sleeved on this gudgeon is a pinion 31 formed on its lower face with a diametrical slot 32 which 105 receives a pair of fixed studs carried by the face of the worn gear 27. With this construction the plate 30 need be only made of suffi-

cient size to enable the removal of the gear 24, and the parts 27 and 31 can be contained in a pocket which is accessible only from the inside of this gear box; for upon loosening 5 the screw 29 and removing the gudgeon 28, the pinion 31 can be slid laterally as soon as its slot has been turned in the proper direction, after which the worm gear 27 can be removed with each. In this way a gear box 10 is provided having only a single circular cover and having its bottom part entirely imperforate so that the gears can be packed in grease without danger of leakage which would spoil the clothing.

15 The free end of the arm 15 is provided with a downwardly opening spherical socket 35 loosely receiving the ball 36 from which depends the cylindrical shank 37, said ball being held in its socket by means of a removable gland nut 38 whose projecting portion is here shown as constituting a bevel gear formed with downwardly facing teeth 40. It will be clear that these teeth might equally well be made in the metal of the socket 20 mouth and the gland correspondingly reduced in size. Rigidly secured to the shank 37 is a gear member 41 formed on its upper face with bevel teeth 42 which mesh with the teeth 40; the number of teeth 42 differing 25 slightly from the number of the teeth 40 so that as the one gear is rolled around the other a slow differential movement is produced, the direction of such movement depending upon which of the gears has the larger number 30 of teeth. For practical reasons it is convenient to make the gear 41 smaller than the gear 39 for which reason I prefer that the number of teeth 42 be less than the number of teeth 40 but do not limit myself to such 35 an arrangement.

40 Slidably mounted upon the shank 37 beneath the gear 41 and adjustably secured thereto by the set screw 45 is a yoke 47 having secured to its ends the downwardly facing suction cups 48—48, preferably two in number, although any symmetrical arrangement of plural cups can be employed.

45 In order to prevent splashing of the wash water I provide a cover comprising a suitably sized piece of flexible waterproof fabric 50 preferably having lead buttons 51 or other suitable weights secured at intervals around the margins and adapted to be thrown over the tub and machine, the upper 55 face of the casing being provided with a socket 52 removably receiving the supporting rod 53 by means of which the cover is held above and out of contact with the working 60 parts.

65 The operation of the device is as follows: the rotation of the water causes a slow revolution of the crank 11 which causes the line a—a which connects the center of the ball 13 with the center of the universal joint 18—19

to generate a cone. Accordingly the arm 15 exhibits an up and down movement throughout a corresponding angle, coupled with a lateral rocking movement, as a result of which the gear 39 exhibits gyratory movement about its own center, although that center is continuously changing position owing to the up-and-down movement of the arm. The weight of the cups 48 causes the shank 37 to hang substantially vertically, as 75 a result of which the teeth 42 always, or at least most of the time, remain in mesh with the teeth 39, with the result that the cups present a slow circular progression around the shank 37 as a center, the direction depending upon the algebraic difference and the rate depending upon the arithmetical difference between the number of the teeth. As a result, a very slow swirling motion is produced in the cleansing liquid, and 80 all parts of the clothing are thoroughly and uniformly washed. I have shown the axis of the shank 18 as substantially intersecting the center of the ball 36, and this I find to be the preferable, although not essential, construction. However if the divergence of these axes be too great the motion of the cups becomes unduly wild and the clothing becomes tangled. In case the machine is overloaded either by reason of the 85 presence of an undue amount of clothing in the tub or an attachment of the cups at too low a point on the shank 37, the spring 21 will yield sufficiently to prevent either any 90 stalling of the motor or breakage of the mechanism. In order to remove the arm 15 it is merely necessary to disconnect the collar 20 (I have shown a cotter pin for this purpose, but any detachable device will do) after which the arm can readily be removed 95 from the shank 18 by a swinging movement around the ball 13 as a center, after which the ball can be freely lifted out of the socket 12.

100 I do not restrict myself to the use of toothed gears 39 and 40 since a suitably roughened device, or a ratchet device or numerous other expedients can be employed; I do not limit myself to any particular form of universal joint at either part of the cone 115 crank; I do not restrict myself to the particular gear-train or driving arrangements herein shown; and in general it will be understood that many changes in matters of detail, construction, and arrangement can be 120 made within the scope of my invention, wherefore I do not limit myself to any of the features herein shown except as the same are specifically recited in the claims hereto annexed.

125 Having thus described my invention, what I claim is:

1. In a washing machine in combination, a rotatable crank, a lever pivoted upon a fixed transverse axis which intersects the 130

- crank axis at a distance from the plane of the crank, said lever having a branch which is oscillatable about the longitudinal axis of the lever, said branch having a universal connection with said crank, and washing devices operatively connected to said lever.
2. In a washing machine, the combination with a support of a crank journaled therein, a lever pivoted to said support upon a fixed 10 transverse axis which is spaced from the plane of said crank and in line with its axis, an arm carried by said lever and having universal connection with said crank, and washing devices operatively connected to said lever.
3. In a washing machine the combination with a support, of a crank journaled therein, a lever pivoted to said support upon a fixed axis which intersects the crank axis at a distance therefrom, an arm carried by said lever and movable about an axis which also intersects the crank axis at a distance from the crank and is perpendicular to the pivot axis of said lever, there being a universal joint 20 connection between said crank and arm, and washing devices operatively connected to said lever.
4. In a washing machine the combination with a crank, an arm supported for universal movement about a point on the crank axis which is removed from the crank plane and also having a universal connection to said crank, a lever operatively connected with said arm to swing therewith about a 30 single transverse axis, and washing devices operatively connected to said lever.
5. In a washing machine, in combination, a lever pivoted to swing about a fixed transverse axis and also to oscillate about a longitudinal axis, washing devices operatively connected to the free end of said lever, a branch arm carried by said lever, a crank journaled about an axis which is perpendicular to the first mentioned axis, said arm and 40 crank being connected by a universal joint, and means for rotating said crank.
6. In a washing machine, in combination, a lever pivoted to swing in a vertical plane, washing devices operatively connected to the free end of said lever so as to be raised and lowered thereby, an arm projecting laterally from said lever and movable about an axis which is perpendicular to the lever axis, a crank journaled about an axis which is perpendicular to both the first mentioned axes and connected to said arm by a universal joint, and means for rotating said crank.
7. In a washing machine, in combination, a support, a crank journaled thereto upon a vertical axis, a lever pivoted to swing upon a fixed horizontal axis which intersects the first axis at a distance from the plane of the crank, an arm projecting from said lever and having a universal connection with the 50 crank, said arm being movable about an axis which is perpendicular to the point of said lever, and a washing device operatively connected to the free end of said lever.
8. In a washing machine, in combination, a support adapted to be secured to the edge of a tub, a lever pivoted thereto upon a fixed horizontal axis and overhanging the tub, washing means carried by the free end of said lever, a crank journaled to said support upon an axis which intersects said first axis, 70 an arm carried by said lever and immovable relatively the first mentioned pivot axis but movable relatively to an axis which is perpendicular thereto, said arm having a universal connection with said crank, and means for rotating said crank.
9. In a washing machine, in combination, a support adapted to be secured to the edge of a tub, a vertical shaft carried thereby, a crank carried by said shaft, an electric motor 85 carried by said gear box outside said tub and having a horizontal shaft, speed reducing gearing operatively connecting said motor shaft and vertical shaft, a lever pivoted to said support upon a horizontal axis and 90 overhanging said tub, washing means carried by the free end of said lever, and mechanism connecting said upright shaft with said lever adapted to oscillate the lever upon the rotation of said shaft.
10. In a washing machine, in combination, a support adapted to be secured to the edge of a tub, a lever pivoted thereto upon a horizontal axis and adapted to project over the tub, a plurality of suction cups depending from the free end of said lever, an electric motor carried by said support, and mechanism whereby said lever is oscillated when the motor is operated.
11. In a washing machine, in combination, 95 a support adapted to be secured to the edge of a tub, a lever pivoted thereto upon a horizontal axis and adapted to project over the tub, a member depending from the end of said lever and rotatable about a vertical 100 axis, a plurality of suction cups carried by said member and disposed symmetrically therearound, an electric motor carried by said support adapted to oscillate said lever, and means for rotating said cups about the 105 axis of said member as said lever is oscillated.
12. In a washing machine, in combination, a support, a lever pivoted thereto and adapted to project over a washtub, said lever 110 adapted to have a swinging movement about a horizontal axis transverse to its own length and also an oscillating movement about its longitudinal axis, means for simultaneously swinging and oscillating said lever, a plurality of suction cups depending from the free end of said lever, and means operated by the oscillating movement of said lever for rotating them slowly about a vertical 115 axis.

13. The combination with a receptacle for clothing and liquid of a lever projecting thereover and pivoted for movement in a vertical plane, a vertically pivoted member 5 depending from the free end of said lever, a plurality of pounders carried thereby, a gear carried by said member, a toothed member carried by said lever and engaging said gear, and means for swinging said 10 shaft so as to reciprocate and rotate said pounders.

14. The combination with a receptacle for clothing and liquid of a lever projecting thereover and pivoted for movement in a 15 vertical plane, a vertically pivoted member depending from the free end of said lever, a plurality of pounders carried thereby, a bevel gear carried by said member, a second bevel gear carried by said lever and 20 adapted to engage said first gear, and means for oscillating said lever about its longitudinal axis simultaneously with its movement about its transverse axis.

15. In a mechanical movement, in combination, a support, a lever pivoted thereto about two rectangular axes, one of which is parallel to the length of the lever, a laterally projecting member carried by the free 25 end of said lever and connected thereto by 30 a ball joint, intermeshing gears carried by said member and lever and having an unequal number of teeth, and means for moving said lever about both its axes.

16. In a washing machine, the combination 35 with a tub, of a lever pivoted to one edge thereof upon two rectangular axes, one of which is horizontal and transverse to the length of the lever and the other of which is parallel to the length of the lever, a vertical shank secured to the free end of said 40 lever by a ball joint, a plurality of suction cups carried by said shank, a pair of intermeshing gear members carried by said lever and shank, and means for rocking said lever 45 about both axes.

17. In a washing machine, the combination 50 with a tub, of a lever pivoted to one edge thereof upon two rectangular axes, one of which is parallel to the lever and the other of which is transverse thereto and horizontal, the free end of said lever having a downwardly opening spherical socket 55 which is substantially in line with the first described axis, a vertically depending shank having a ball end received in said socket, pounders carried by said shank, and means for oscillating said lever about both axes.

18. In a washing machine, the combination 60 with a tub, of a lever pivoted to one edge thereof upon two rectangular axes, one of which is parallel to the lever and the other of which is transverse thereto and horizontal, an arm projecting vertically from said lever, a horizontal crank articulated to said arm and having its axis inter- 65

secting the junction of said first two axes, and pounders carried by the free end of said lever.

19. In a device of the character described, in combination, a gear box, a shaft journaled 70 therein and having a crank, a bracket carried by the side of said box opposite to said crank and having a pivot axis which intersects the crank-axis perpendicularly, a pivot member journaled therein and having 75 a second pivot axis perpendicular both to the crank axis and to the first pivot axis, a lever journaled to said pivot member with its length parallel to said second pivot axis, and a side branch carried by said lever having 80 universal connection with said crank.

20. In a washing machine, a bracket adapted to be secured to the rim of a wash tub and having a horizontal journal bearing, a rocker member pivoted therein and having 85 a shank perpendicular to the pivot axis, a lever having a horizontal bore slidably mounted on said shank, a spring yieldingly drawing said lever onto said shank, pounders carried by the free end of said lever, an 90 arm projecting upwardly from said lever, and operating means connected to said arm.

21. In a washing machine, in combination, a gear box having a crank projecting from one side and a bracket projecting from the 95 other side, said bracket having a bearing therein whose axis intersects the crank axis perpendicularly, a clamp device whereby said gear box may be secured to the rim of a tub with said crank axis vertical and 100 said bearing horizontal, an electric motor carried by said gear box and operatively connected to said crank, a lever pivoted to said bearing and having a side arm which is operatively connected to said crank, and 105 a pounder connected to the free end of said lever.

22. In a washing machine, in combination, a gear box made in the form of an upwardly opening casing having an imperforate bottom, a clamping device adapted to secure said gear box to the edge of a tub, a crank carried by said box and projecting upwardly, an electric motor carried by said box and projecting outside the tub, a lever 110 pivoted to said box on a horizontal axis and projecting over the tub, pounders carried by the free end of said lever and operative connections between said crank and lever.

23. In a washing machine, in combination, a supporting member adapted to be detachably connected to the edge of a wash tub, an electric motor secured thereto, pounder mechanism carried by said member and operatively connected to said motor, and 115 a flexible cover having weighted edges adapted to cover said mechanism, member, and motor and to hang down around the tub.

24. In a washing machine, in combina- 130

tion, a supporting member adapted to be detachably connected to the edge of a wash tub, an electric motor secured thereto, a pounder mechanism carried by said member and operatively connected to said motor, an arm adapted to be carried by said member and to project over such mechanism, and a flexible fabric cover adapted to be supported by said arm so as to house such mechanism and member, and having weighted margins 10 adapted to hang outside of said tub.

In testimony whereof, I hereunto affix my signature.

JAMES B. KIRBY.
